Attorney*

UNITED STATES PATENT OFFICE.

WILLIAM O. THOMPSON, OF CLEVELAND, OHIO.

END STRUCTURE FOR RAILWAY CARS.

Application filed January 11, 1924. Serial No. 685,601.

To all whom it may concern:

Be it known that I, WILLIAM O. THOMPSON, residing at Cleveland, county of Cuyahoga, State of Ohio, and being a citizen of the United States, have invented certain new and useful Improvements in End Structures for Railway Cars, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

The ends of railway cars are subject to considerable stress due to the shifting of the lading which is caused by the heavy locomotives, the automatic air brake, the hump and other modern railway service conditions. These thrusts may be local, tending to distort the end in some particular spot, as, for example, when a piece of piping or lumber shifts lengthwise, or a load of plastic material, such as grain, sand or chaffs may shift, imparting a blow over a large area of the end wall, whereas rail, steel plates, castings and the like cause blows at the bottom of the car. From the above, it is apparent that a railway car end must be strong throughout its entire area. Experience shows that a stronger end wall is needed adjacent the floor of the car because the blows against this portion of the car wall are more frequent and more severe than at the middle or upper portion thereof. Very little strength is needed adjacent the top of the car wall and the strength required at the middle of the car wall is more than needed at the top and less than needed at the bottom.

While, of course, efforts are made to block the lading in the car, the shocks caused by the heavy locomotives, the emergency air brake and the classification hump tear the lading away from its moorings and throw it against the side walls of the car.

A rigid end to a car, and particularly a large car, materially strengthens the entire superstructure to resist the torsional and weaving movements which not only rack the

car to pieces, but causes leaky roofs and inoperative and leaky doors with their consequent damage claims. As it costs as much to transport a ton of freight car as it does a ton of lading it is imperative that the weight of the car must be kept as low as possible, therefore, the end must be very light as well as strong. As freight cars are frequently damaged in wrecks and by other unfair usage, any end will be damaged in service, therefore, it must be capable of being easily repaired with such meagre facilities as the railroads are equipped with at their outlying repair points.

My invention relates to the construction of railway cars and more particularly to metal end structures or walls for railway cars made of one or more metallic plates or panels formed with integral reinforcing stiffening or bracing corrugations. However, the construction may be used in car side walls. It is readily adaptable to box, gondola, stock or other types of railway equipment.

Car ends have been constructed with thin metallic plates with integral reinforcing corrugations formed therein, which sheets or panels cover a large part of the end wall of the car.

As stated before, a stronger end wall is needed adjacent the floor of the car because the blows against this portion are more frequent and more severe than elsewhere. When one of these large panels is bulged or damaged it is difficult and expensive to remove such a large portion of the end wall, and, furthermore, if this large panel was made of sufficient thickness of material to withstand the shocks adjacent the floor of the car it would be too heavy for practical purposes; also it would be difficult to press the corrugations in the sheet, and, furthermore, prohibitive as to cost.

One of the objects of my invention is to provide a separate sub-end sill which may be made of sufficient thickness of material and so formed as to resist these severe and frequent shocks adjacent the floor. This sub-end sill occupies very little area of the end wall and is so arranged that the corrugated panel may be attached to its upper part and its lower part may be attached to the framing of the car.

Another object of the invention is to provide a sub-end sill having the advantages

described in the preceding paragraph which sub-end sill performs the further function of tying together the center sills the side sills the end sill the corner post and the 5 corrugated end panel, thereby reinforcing what is commonly known to be one of the weak points of present day car construction.

In the drawings:

10 Fig. 1 is an end elevation of a gondola car with my invention applied thereon.

Fig. 2 is a section on line 2—2 taken in the direction as indicated by the arrows of Fig. 1.

15 The drawings show an ordinary type of gondola wherein the floor sheet 1 extends over and is secured to the top of the end sill 2 and center or draft sills 3. The striking casting 4 is usually placed on the 20 outside of the end sill as shown. The corner post 5 is angular in shape and has one leg secured to the end sill 2 by rivets 6 and has the other leg secured to side sill 7 by rivets 8. The end wall of the car 9 is secured to 25 the corner post 5 by rivets 10 which end wall may be reinforced with integral corrugations 11, as shown, or any other desired manner. The upper part of end wall 9 is formed with flange 12 and reinforced by 30 stiffening member 13. The upper part of the side wall is reinforced by member 14. The upper part of the side and end walls may be secured together in any desired manner, such as by member 15.

35 The sub-end sill is made of thicker material than the end wall 9 and is provided with horizontal flange 16 which is secured at various points to the sill 2 by rivets 17 and to the draft sills 3 by rivets 18. The 40 portion 16 is also secured to the side sill 7 by rivets 19. The sub-end sill is provided with a flange 20 at its upper part which is secured to the end wall 9 by rivets 21. The vertical part 22 of the sub-end sill occupies 45 that portion of the end wall adjacent and just above the upper surface of the floor of the car, and being of heavy material and reinforced against horizontal thrust by flanges 16 and 20, enables it to resist the 50 horizontal thrust caused by the shifting of the lading.

I claim:

1. In combination with the side sills, center sills and metallic end wall of a railway car provided with integral horizontal corrugations a sub-end sill of thicker material than said end wall having a vertical web forming the lower part of the end wall, and having an inwardly projecting horizontal flange secured to the center and side sills, the upper part of said sub-sill connected to the metallic end wall. 55

2. In combination with the side sills, center sills, corner posts and metallic end wall of a railway car provided with integral horizontal corrugations a sub-end sill of thicker material than said end wall having a vertical web forming a part of the end wall secured to said corner posts, and having a lower inwardly projecting horizontal flange secured to said side sills and center sills, and having an upper outwardly projecting horizontal flange secured to said metallic end wall. 65 70

3. In combination with the side sills, center sills, and metallic end wall of a railway car provided with integral horizontal corrugations; a sub-end sill of thicker material than said end wall having a vertical web forming the lower part of the end wall, 80 and having an inwardly projecting horizontal flange secured to the center and side sills, the upper part of said sub-sill connected to the metallic end wall, the inside of said corrugated end wall being flush with the inside of the vertical wall of said sub-end sill. 85

4. In combination with the side sills, center sills, corner posts and metallic end wall of a railway car provided with integral horizontal corrugations; a sub-end sill of thicker material than said end wall having a vertical web forming a part of the end wall secured to said corner posts, and having a lower inwardly projecting horizontal flange secured to said side sills and center sills, and having an upper outwardly projecting horizontal flange secured to said metallic end wall, the inside of said corrugated end wall being flush with the inside of the vertical wall of said sub-end sill. 90 95

WILLIAM O. THOMPSON.
